UNITED STATES PATENT OFFICE

169,111

BOTTLE

Frasier Smith, Elm Grove, W. Va., assignor to
The Kiwi Polish Company Proprietary Limited,
Richmond, near Melbourne, Victoria, Australia,
a corporation of Victoria

Application November 6, 1952, Serial No. 22,171

Term of patent 14 years

(Cl. D58—6)

To all whom it may concern:

Be it known that I, Frasier Smith, a citizen of the United States, residing in Elm Grove, in the county of Ohio and State of West Virginia, have invented a new, original, and ornamental Design for a Bottle, of which the following is a specification, reference being had to the accompanying drawing, forming part thereof.

Fig. 1 is a perspective view of a bottle, showing my new design.

Fig. 2 is a plan view of the same.

The opposite side and edge of the bottle, not shown, are the same as the side and edge shown.

I claim:

The ornamental design for a bottle, as shown and described.

FRASIER SMITH.
